(57) **CLAIM**

The ornamental design for a suspension mechanism for a curtain, as shown and described.

DESCRIPTION

FIG. 1 is a front and left side perspective view showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top elevation view thereof;

FIG. 7 is a bottom elevation view thereof;

FIG. 8 is an exploded view of the components of the suspension mechanism for a curtain; and,

FIG. 9 illustrates a plurality of the suspension mechanisms between a curtain and a suspension rail.

The broken lines depict unclaimed environmental subject matter.
